UNITED STATES PATENT OFFICE.

FRANK LA OTIS LATHROP, OF WALLINGFORD, CONNECTICUT, ASSIGNOR TO H. L. JUDD & COMPANY, OF WALLINGFORD, CONNECTICUT, A CORPORATION OF NEW YORK.

CURTAIN-ROD BRACKET.

1,150,274.

Specification of Letters Patent. Patented Aug. 17, 1915.

Application filed February 3, 1915. Serial No. 5,813.

To all whom it may concern:

Be it known that I, FRANK LA OTIS LATHROP, a citizen of the United States, residing at Wallingford, county of New Haven, in the State of Connecticut, have invented certain new and useful Improvements in Curtain-Rod Brackets, of which the following is a full, clear, and exact description.

10 This invention relates to an improved curtain rod bracket, the object being to provide a simple and inexpensive structure which admits of ready attachment and detachment of the curtain rod, and which is 15 effective to hold the same in place and prevent accidental disengagement.

A preferable embodiment of the invention is illustrated in the accompanying drawings forming a part of this specification, in which,—

Figure 1 is a front elevation of a pair of brackets with the curtain rod supported therebetween, parts of the brackets being shown in section. Fig. 2 is a horizontal 25 sectional view through one of the brackets shown in Fig. 1, on an enlarged scale. Fig. 3 is a vertical section on the line 3—3 of Fig. 1. Fig. 4 represents, in elevation, the parts forming the bracket before being assembled.

Referring to the drawings by numerals, 1 designates a curtain rod, which may be of any suitable or standard construction.

2 and 3 designate, generically, brackets arranged to support the opposite ends of this rod. In the particular form of bracket element shown herein, wall plates 2^a—3^a are provided, having bracket rods 2^b—3^b extending therefrom, these rods in the particular embodiment shown, being bent or curved and receiving the bracket connections. A description of the specific construction of a single bracket connection will suffice inasmuch as the construction for both 45 brackets may be the same. A bracket rod, say 2^b, adjacent its end is formed with a recess preferably in the form of an annular groove 4 therein, which is designed to act as a pocket to receive and hold a drag or 50 friction means. This means is in one form, a split spring ring 5 which may be forced over the end of the bracket rod 2^b so that it may snap into the pocket formed by the annular groove 4 and be held by the adjacent 55 sides of the groove against accidental dis-

placement therefrom. This spring ring 5 is of a size and cross-section to project materially beyond the periphery of the adjacent surface of the bracket rod and is preferably formed to permit slight contraction or expansion after being seated within the groove 4. A coupling sleeve 6 is provided for connecting or coupling the bracket element with the curtain rod, this coupling sleeve being of an internal diameter greater than the external diameter of the bracket rod and is sufficiently large to slide over the split ring 5 when the latter is in place and slightly compressed. The internal diameter of the sleeve is nevertheless such as to create substantial friction between its inner sleeve surface and the outer surface of the spring ring when the sleeve slides over the ring. Toward its outer end this sleeve is formed with an annular groove or indentation providing an annular shoulder 7 positioned and designed to engage the ring 5 when the sleeve is moved inwardly so as to bring the outer edge of the sleeve and the outer end of the bracket rod in substantially the same 80 plane.

In assembling this fixture, the split ring 5 is first slid over the end of the bracket rod and into the annular groove or pocket 4. The sleeve 6 is then slid over the end of the 85 bracket rod, its inner surface engaging and slightly contracting the spring ring. When the sleeve has thus been mounted upon the bracket rod its inner end is turned down or contracted, as at 8, forming a stop to prevent the withdrawal of the cylinder from the bracket rod and spring. The operation of assembly is seen diagrammatically in Fig. 3 of the drawings wherein the parts are illustrated in separated position with 90 the inner end of the sleeve 6 opened out so that it may be forced over the spring ring.

From the foregoing it will be obvious that in order to mount a curtain rod between the brackets 2 and 3 the bracket sleeves need 100 only be moved backwardly until substantially coincident with the outer ends of the bracket rods, the curtain rod 1 is then fitted therebetween and the bracket sleeves are then moved outwardly over the ends of the 105 curtain rods which are supported between these sleeves, the sleeves in turn being supported by the bracket rods. The friction of the sleeves on the spring rings is sufficient to hold them in the rod engaging position 110

under ordinary circumstances, but is not sufficient to prevent intentional sliding back of the sleeves to release the curtain rods. It will be noted that the annular shoulder 7 of the bracket sleeves may be utilized not only as a stop for the inward sliding movement of the sleeve but also may serve to take part of the strain of the support of the curtain rod, and the same is also true of the contraction 8.

It will be noted that the overall thickness of the wire constituting the split ring 5 is greater than the space between the outside of the rod and the inside of the ring, hence 15 part of the ring will always extend into the recess 4 to be held by the side walls thereof.

The bracket fixture herein described is of extremely simple construction and is effective to attain the objects mentioned.

20 While the foregoing description is necessarily a detailed one in so far as it concerns the particular bracket fixture selected for illustration, it will be apparent that the structure is susceptible of various modifications 25 within the spirit of the invention and the scope of the appended claims. It is to be noted also that the friction means,—in this specific form, the spring ring,—acts as an abutment or stop for the sleeve shoulders, 7—8, although this function is merely incidental and auxiliary and is not essential 30 to the proper functioning of the ring as a resilient friction medium.

What I claim therefore and desire to secure by Letters Patent is:

1. In combination, a curtain rod bracket having a rod portion provided with an annular groove therein, a split spring ring located within said groove and partially 40 projecting therefrom, a coupling sleeve inclosing and sliding over said bracket rod portion, said spring ring frictionally engaging said sleeve and retaining it in adjusted position on said rod portion and 45 against accidental displacement from such position, with means whereby said sleeve is retained on said rod portion.

2. In combination, a curtain rod bracket having a rod portion provided with an annular groove therein, a split spring ring located within said groove and partially 50 projecting therefrom, a coupling sleeve inclosing and sliding over said bracket rod portion, said spring ring frictionally en-

gaging said sleeve and retaining it in adjusted position on said rod portion and against accidental displacement from such position, such sleeve having stop shoulders coöperating with said bracket element and split ring to limit the movement of said 60 sleeve thereon in opposite directions.

3. In combination, a curtain rod bracket element, a curtain rod connector element slidably mounted on and inclosing said bracket element, with a yielding annular 65 friction member interposed between said elements and operatively engaging both elements to retain said sliding connector in adjusted position relative to said bracket element.

4. In combination, a curtain rod bracket element, a curtain rod connector element slidably mounted on and inclosing said bracket element, with a spring friction ring 75 interposed between said elements and held under compression by said outer element and arranged to retain said sliding connector in adjusted position relative to said bracket element.

5. In combination, a curtain rod bracket 80 element providing a pocket, a split spring ring seated in said pocket, a connector sleeve inclosing said bracket element and ring and 85 slidably relative thereto, said ring frictionally engaging said sleeve to retain the same in adjusted position relative to said bracket.

6. In a curtain rod bracket, a rod, a sleeve slidably mounted thereon, a combined abutment stop and friction device arranged 90 between said rod and sleeve and arranged to limit the sliding movement of the latter on the former and to frictionally hold the latter in operative rod-engaging position.

7. In a curtain rod bracket, a rod, a sleeve slidably mounted thereon, a combined abutment stop and friction device arranged between said rod and sleeve and arranged to limit the sliding movement of the latter on the former and to frictionally hold the latter in operative rod-engaging position, 100 said combined abutment stop and friction device comprising an expansible split ring, said rod having an annular groove loosely receiving said ring.

FRANK LA OTIS LATHROP.
